UNITED STATES PATENT OFFICE.

HENRY H. SLINGERLAND, OF CHICAGO, ILLINOIS.

SOUND MODIFIER FOR STRINGED INSTRUMENTS.

Application filed November 9, 1921. Serial No. 513,905.

To all whom it may concern:

Be it known that I, HENRY H. SLINGERLAND, a citizen of the United States, residing at Chicago, in the county of Cook and 5 State of Illinois, have invented a new and useful Improvement in a Sound Modifier for Stringed Instruments, of which the following is a specification.

My present invention relates to a structure for modifying the tone of stringed musical instruments wherein the vibrations of the strings are communicated to a vibratile member through the instrumentality of an interposed bridge.

15 The special object of my invention is to provide an added resonant element, or elements, which will be set in vibration by the vibration of the strings and their said supporting vibratile element through the well-known principles of resonance and consonance, and also relates to means for setting free the sounds that have thus been augmented and modified.

20 My present invention is an extension of 25 the principles employed in my previous invention set forth in the application filed by me September 2, 1921, Serial Number 497,845, for stringed musical instruments, and, as will be seen, embodies a simplified 30 construction operating in a different manner (and producing sounds differing in volume and quality). I prefer to attain the objects of my present invention by the means and in the manner hereinafter described, and as 35 more particularly pointed out in the appended claims, reference being had to the accompanying drawings that form a part of this specification, in which—

40 Figure 1 is a fragmental side elevation of the body end of a banjo in which my invention is embodied, a portion of the side of the head being broken away to show the interior arrangement.

45 Figure 2 is an enlarged fragmental sectional detail of the structure shown in Fig. 1.

50 In the drawings, I have employed similar reference characters to designate like parts throughout the several views.

55 I have shown my invention in combination with a typical banjo structure consisting of a body portion comprising a cylindrical wall 5 provided around its exterior with brackets 6 of L-shape coacting with the lateral arms which are hooked, or J-shaped clamping rods 7, the hooked ends of which

engage an annular groove 8 in a collar 9 which is proportioned with a slightly larger interior diameter than the exterior diameter of cylindrical wall 5. The cylindrical 60 wall 5 preferably carries upon the top thereof a metal ring 10 of circular section, and across this metal ring is disposed a membrane 11 of sheepskin, or the like, the peripheral edge of which is carried around another metal ring 12 which is of sufficient diameter to surround cylindrical wall 5. The collar 9 encloses the folded portion of the edge of membrane 11 between itself and wall 5, and is drawn down by clamping rods 70 7 to tightly stretch membrane 11 across the end of cylindrical wall 5. The typical banjo also has a neck 13 extending radially from cylindrical wall 5 and diametrically opposite to the location of the neck is secured a 75 tail-piece 14 to which are attached strings 15 extending from the tail-piece to the outer end of the neck where they are appropriately secured.

Supported upon the tightly stretched 80 membrane 11 is a bridge 16 which serves to hold the strings in desired relation with the membrane and neck, and to impart through the material of the bridge the vibrations of the strings directly to the tightly stretched 85 membrane 11. In the ordinary banjo the end of the cylindrical wall 5 opposite that across which membrane 11 is stretched is entirely open and unobstructed, and the sounds which emanate from the under face of the 90 membrane proceed without modification. In my present design, I have located a resonating member or sounding board 17 adjacent the usual open end of cylindrical wall 5 where it will be in position to receive and 95 be set in motion by the vibrations of the air emanating from membrane 11. This resonating member or sounding board 17 is preferably of concavo-convex section arranged with its convex side bulging in or extending 100 towards membrane head 11 at the opposite end of the cylindrical body wall and these elements, i. e., membrane head 11, cylindrical body wall 5 and the resonator or sounding board 17 provide a resonating or sounding 105 chamber the opposite walls or ends whereof are of a vibratory character, whereby the sounds produced by strings 15, and transmitted to this chamber through the intermediary of the bridge and membrane, are 110 augmented and modified in tone. In order to liberate these sounds so that they may be

emanated to the audience, I have provided a plurality of apertures 18 in the cylindrical body wall 5 between resonating member 17 and membrane 11. If desired, the sounding board 17 may be provided with apertures 17^a through which the air affected by both the vibrations from the membrane and the sounding board may pass out of the resonating chamber. I have shown the usual open end of cylindrical wall 5 closed by a cover-piece 19, but this is mainly for the purpose of protecting resonating member 17 and for excluding dust and moisture from the interior of the instrument. For convenience in manufacture and assembly, I prefer to make cover 19 of concavo-convex shape, the curvature thereof corresponding with the curvature of sounding board 17 so that they may both be fabricated with the same die, but for obvious reasons the cover piece is made of heavier material than the sounding board, and when the latter is apertured, I provided a plurality of apertures 19^a in the cover-piece to permit of the liberation of the augmented and modified tones. For the purpose of directing the tones towards the audience, I have connected the inner curved end of a sound-tube 20 around one of apertures 17^a in the sounding board, while the opposite end of the tube, after passing through cylindrical body wall 5 oblique to the line of the strings, is curved in the opposite direction and formed into the bell of a horn 21 that is located alongside the neck 13 adjacent its juncture with the cylindrical body wall 5.

From the foregoing description, taken in connection with the drawings, it will be perceived that I have provided an extremely simple sound modifying device in instruments of the kind described, which will produce consonant over-tones and thereby modify and greatly sweeten the tone of the instrument. It will also be understood that, while I have herein disclosed a single embodiment of my invention, the structure is capable of modification or refinement, and I desire it understood that such changes are

fully contemplated by me as coming within the scope of the appended claims.

What I claim is:

1. A stringed instrument comprising a body wall, resonating elements at opposite ends thereof, one of said elements being in a plane directly below the instrument strings and directly receives the vibrations thereof and the other element being apertured to liberate the sound waves within said body wall, and a horn the entrance to which is connected to the last mentioned resonating element in registry with and surrounding an aperture therein and said horn extending through said body wall and terminating outside the beforementioned structure adjacent the neck.

2. The combination with a banjo, of a closure for the portion of the body opposite the strings; said structure comprising a pair of concavo-convex disks disposed with their concave faces towards each other, the inner disk being centrally apertured; and a horn the entrance to which engages with and surrounds said aperture and the body thereof extends outside the side wall of the banjo and flared outside said wall.

3. The combination with a banjo, of a structure closing the portion of the body opposite the strings; said structure comprising two concavo-convex disks arranged in superposed relation with their concave portions facing each other; said disks being apertured and the inner disk providing a resonator opposite the head of said banjo whereby the sound vibrations of the banjo head are augmented and modified by said resonator disk, and a horn secured to the inner disk at an aperture therein and extending through the body of said banjo.

Signed at Chicago, county of Cook and State of Illinois, this 4th day of November, 1921.

HENRY H. SLINGERLAND.
